SPOUTS

Bert M. Mercer, New York, N. Y.

Application May 25, 1953, Serial No. 357,251

6 Claims. (Cl. 222—81)

This invention relates to spouts for pasteboard boxes and the like and comprises a device by which the box is punctured for creating a discharge opening which is closed by the spout except at such times as it is desired to pour contents from the box.

An object of the invention is to provide an improved sturdy and rigid construction of spout which is simple in construction and readily understood by the prospective user both as to manner of insertion and use and removal for re-use.

In its broad aspects, the invention contemplates an improved spout having inherent piercing and cutting mechanism for creating the precise size of opening necessary for insertion of the spout and which can be applied to tightly fit the hole which it makes and yet removable in its entirety, when desired, for use in a different box.

A more specific object of the invention is to provide a novel spout which may be rocked into its position of use and which will obtain tight contact with the wall of the box in which it is inserted and which will confine the pouring of the box contents to the channel provided within the spout itself.

Another object of the invention is to provide a spout of economical character which occupies minimum space within the box and which will afford full control of the discharge of the contents and only permit discharge of the contents when the box in which it is used is tilted.

Another object of the invention is to provide a spout which will remain securely closed until manually opened and a spout which will remain securely located in position of application as long as it is needed, and yet easy to remove for further use subsequently in another box.

Yet another object is to provide a construction which may be formed from flat blanks and made up of a minimum number of easily assembled parts.

Other objects of the invention will appear to persons skilled in the art to which it appertains as the description proceeds, both by direct recitation thereof and by implication from the context.

Referring to the accompanying drawing, in which like numerals of reference indicate similar parts throughout the several views:

Figure 1 is a front elevation of the spout in its closed condition;

Figure 2 is a vertical sectional view on line 2—2 of Fig. 1;

Figure 3 is a cross-sectional view on line 3—3 of Fig. 1;

Figure 4 is a vertical sectional view similar to Fig. 2 showing the spout in open condition ready for pouring contents from the box;

Figure 5 is a sectional view of the spout in the process of being inserted in the box, showing the spout being rocked to assume its final position; and

Figures 6 and 7 are perspective views of the spout looking at the same from opposite directions.

In the specific embodiment of the invention illustrated

2

in said drawing, reference numeral 10 indicates a box or carton in general, having a side wall 11 through which the spout is inserted by punching its own opening; and 12 designates the top wall of the box or carton. It will be appreciated that the user has the latitude of choice as to where to insert the spout, and the particular location indicated in the drawing, while being preferable, is not to be understood as an invariable requirement. The device is constructed from sheet metal of appropriate rigidity such that its body portion 13, formed as a channel, may be forced through the pasteboard of a box or carton and cut its own opening. The channel formation is preferably constructed with a pointed nose 14 terminating the inner end of the bottom thereof and the inner ends of the side walls 15 of said channel formation slope upwardly rearward, and consequently as the channel is pushed into the carton, the sloping edges progressively slit the pasteboard, forming a tab which it forces inwardly of the box and which it swings upwardly toward the top of the box.

The bottom wall of the channel formation is provided with a discharge opening which extends for the full distance between the side walls of the body and also extends between the rear end of the nose 14 to an end piece

25 16 at the far end of the opening. Said end piece integrally connects the margins of the side walls next to the ends thereof rearward from the nose. This end or cross-piece 16, in use, is bent so as to provide a stop or ledge 17 substantially in the plane of the bottom wall of the

30 body portion to limit inward swing of the lid 18 hereinafter referred to, and to also provide a frame section 19 to extend across the face of the wall 11 of the carton at the top of the punctured hole when the device is in place. This frame section may be doubled back upon

35 itself, so that its free edge is directed toward the opening. At the rear of the frame section 16 the metal is bent at right angles forming a shoulder 19a to the upper end of afore-mentioned ledge 17. The lower end of the ledge 17 toward the opening is preferably bent inwardly

40 and provides a lip 20 adapted to engage the tab 21 of the box material which is forced inwardly when the opening is cut by the walls of the channel member. Normally, however, the tab will be engaged at its margin by the edges of the side walls of the channel member and will

45 be bent upwardly out of the way as clearly shown in Figures 2 and 4, the lip being provided as a safety measure in the event it should be needed by the tab's forcing its way between the said side walls of the channel member.

The rear end of the nose 14 next to the opening in the bottom wall is curled or otherwise formed to provide a hinge stock 22, the same cooperating with aligned hinge stock 23 on the afore-mentioned lid 18 and receiving a pin 24 for hinging the lid at the rear end of said nose. The lid has a body portion which will fully close

50 the opening and extends further than the opening so as to engage the afore-mentioned stop or ledge 17 when the lid is closed, and at that edge of the lid, the same is offset at 25 and provided with an extending finger-piece 26.

55 A detaining knob 27 is bent up from the offset 25 to snap under the edge of the front part of frame section 19 so as to retain the lid closed until the user exerts positive force upon the finger-piece to swing the lid down. It is preferable to provide an ear 28 at the hinged end of the lid, said ear projecting outwardly with a face

60 thereof in the path of outward movement of the lid so it will limit the swing permitted for the lid, as shown in Fig. 4, the parts being so proportioned that the lid will slope outwardly upward in its most open position and thus require that the package be tilted before the contents of the package will discharge from the opening of the swung lid. Said lid has side flanges 29 which swing

in flatwise engagement against the side walls of the channel member and consequently form a chute for the contents of the box to flow through when the box is tilted and the lid is open.

The forward ends of the side walls of the channel member are preferably, in general, perpendicular to the bottom wall of the channel and are provided with teeth 30, of the nature of saw-teeth, so that when the device is inserted in place in a carton, the said teeth will grip against the bent tab of the box and will resist any tendency of the device to move outwardly from the puncture or hole. In order to supplement the retaining characteristic of the saw-tooth edge of the end edges of the side walls of the channel member, lugs 31 may be stamped outwardly from said side walls in position to engage behind the side margins of the puncture or hole punched in the box.

Upon applying the device to a box, the pointed nose 14 is punched through the side wall 11 of the box and continued pressure moving the device longitudinally inward will sever the box material crosswise under the entire nose and then the end edges of the side walls of the channel member begin to cut the box wall upwardly from the transverse cut and the intervening tab is bent upwardly by engagement with said side walls of the channel member. The device is forced inward substantially as far as the line of hinging at the rear end of the nose whereupon the device is rocked upwardly to bring the frame member 16 upwardly against the side of the box being pierced toward the top of the puncture or hole therein. In this connection it may be stated that the maximum perpendicular height of the side walls of the channel member are shown approximately equal to the distance of the hinge stocks 23 to the shoulder 19a and likewise that the toothed perpendicular end edge is substantially in the plane of said shoulder so that the hole punched by the said side walls will be substantially equal in area to that required to receive the shoulder and teeth therein when the device is rocked to its upright position.

As a further refinement, the device may be provided with outwardly extending flanges 32 integral with the channel member and extending outwardly from the lid opening so as to overlie the margin of the hole cut in the box. These flanges, in conjunction with the hinge stocks at the bottom and the frame section 19 at the top constitute a complete frame for the punched hole in the box or carton.

It is further to be noted that the nose 14 is of a grill construction, leaving apertures 33 therein through which the powder or flake contents of the box may pass while the device is being swung to its vertical position and thus avoid having the contents of the box interfere with proper placing or positioning of the nose flatwise against the inside of the box.

If so desired, a stop may be provided next to the line of hinging spaced from the bottom wall of the channel member, this stop being herein illustrated as a finger 34 sliced from the hinge stock 22 intermediate the ends thereof. Said finger will engage the face of the carton wall and act as a stop and rocking pivot when the nose 14 is punched into the box, and with the stop and hinge stocks brought into engagement with the face of the box next to the punctured hole the device may be rocked thereon through the hole to final position. In such final position, the nose is located against the inside of the box wall below the punctured hole and the upper frame section 19 and flanges 32 are located on the outside of the wall around the other three sides thereof with the lid 18 adapted to close the opening of the body portion 13 and keep the contents from spilling.

I claim:

1. A spout for puncturing a hole in and detachably remaining in said hole of a carton, comprising a channel body constructed to pierce a wall of a paperboard carton

and to be completely inserted into said hole of the carton, and a series of saw-teeth on the rear end of said channel located to make continuous contact with and grip the opposing pasteboard in final mounted position of said channel body in the carton to prevent displacement of the spout from its inserted position.

5 2. A spout for puncturing a hole in and detachably remaining in said hole of a carton, comprising a channel body having a substantially planar bottom wall the length 10 whereof provides front and rear portions, said front portion being constructed to pierce a wall of a carton and said rear portion providing a discharge opening there-through, said bottom wall having a transverse means projecting from the under side thereof at the junction of said 15 front and rear portions and contiguous to said opening and functioning as a stop for limiting longitudinal insertion of said body into a carton thereat and thereby, said body being insertable by cutting its way through the wall of a carton as far as said transverse means with the 20 said rear portion protruding at the outside of said carton, said channel member providing longitudinal side walls cooperating with the forward piercing end of the bottom wall of said channel body to make a three-sided cut and thereby pierce a hole and produce a flap thereat in front 25 of the side walls of said channel body, and the top edges of said side walls being curved for enabling the channel body to be rocked about said stop means as an axis and thereby introduce the side walls of said rear portion into the hole punched by the front portion of the channel 30 body, said channel side walls terminating with rear edges substantially perpendicular to the plane of the bottom wall, said rear edges of the side walls having teeth engageable with the partially cut and bent-in flap of the carton in final position of the bottom wall of 35 the channel body rocked into juxtaposition flatwise against the carton wall.

3. A spout in accordance with claim 2, wherein a transverse lip is provided located between said side walls of the channel body with the edge of said lip on a line intersecting said side walls proximate to said curved edges and to said rear edges of said side walls.

4. A spout in accordance with claim 2, wherein the rear margin of the bottom wall of said channel is bent back upon itself and offset in a direction toward said 45 curved edges for providing a ledge at the rear part of said opening, and a lid hinged at the forward edge of said opening and engageable with said ledge.

5. A spout in accordance with claim 2, wherein the rear margin of the bottom wall of said channel is bent back 50 upon itself and offset in a direction toward said curved edges for providing a ledge at the rear part of said opening, a lid hinged at the forward edge of said opening and engageable with said ledge, and a transverse lip bent from said ledge and located between said side walls of the channel body with the edge of said lip in a line intersecting said side walls proximate both to said curved edges and to said rear edges of said side wall.

6. A spout in accordance with claim 2, wherein the opening is provided with a hinged lid, and said lid provides flanges projecting at its sides between and in slidably 60 engagement with said side walls of said channel body, said lid and its flanges in open position constituting a chute for pouring material coming from said carton and guided to said chute by said side walls of the channel body.
